UNITED STATES PATENT OFFICE.

CHARLES H. ELLIOTT AND GEORGE W. ELLIOTT, OF ROCKFORD, IOWA.

SHEAF-CARRIER.

SPECIFICATION forming part of Letters Patent No. 379,212, dated March 13, 1888.

Application filed September 5, 1887. Serial No. 248,881. (No model.)

To all whom it may concern:

Be it known that we, CHARLES H. ELLIOTT and GEORGE W. ELLIOTT, citizens of the United States, residing at Rockford, in the 5 county of Floyd and State of Iowa, have invented a new and useful Improvement in Bundle-Carriers for Harvesters, of which the following is a specification.

This invention relates to bundle-carriers for harvesters; and it consists in the improvements hereinafter described, whereby a simple and efficient dumping-platform is provided, and one whose tilting movements may be readily limited and controlled.

15 In the accompanying drawings, forming part of this specification, Figure 1 is a perspective view of a portion of the frame of a harvesting-machine having our improved sheaf-carrier applied thereto. Fig. 2 is a front view 20 representing the platform in a tilted position.

A designates one of the transverse sills of the harvester-frame, to the ends of which are connected the sills B, which extend a short distance beyond the bar A to form projections 25 a. A vertical curved metallic arm, C, is rigidly secured at its lower end to each projecting portion a, and at the upper end of said arm one leg, b', of an irregular U-shaped arm, b, is pivotally secured, the said U-shaped arm 30 being rigidly connected to the sides D of the sheaf-carrier G. The arm b' has integrally formed therewith another leg, c, which extends inwardly at a slight divergence from the leg b', and has its upper end, d, bent horizontally 35 inward slightly over the sheaf-carrier.

A vertical arm, E, is secured to the outer side of the sheaf-carrier, and has its upper end perforated for the engagement of a wire rod or cable, f, the other end of which is connected 40 to a bell-crank lever, F, pivoted on the harvester-frame. The dropping movement of the platform is limited by the inwardly-bent horizontal portion d of the leg c coming in contact with the under side of the arm C.

45 The sheaf-carrier comprises a rectangular frame, G, which is open on the side next the sill A, and a platform, H, made of slats I, supported on longitudinal bars K, that connect the front and rear sides of the frame. The slats I 50 are arranged transversely, so that when the

carrier is tilted, as shown in Fig. 2, the sheaves will slip smoothly over the slats and be discharged upon the ground.

It will be observed that the arm b is connected to the inner open portion of the sheaf-carrier D, so that when the said carrier is tilted the weight thereof is sufficient to overbalance and insure the dropping of the said carrier back to a horizontal position, as shown in Fig. 1.

The operation of our invention is as follows: When the carrier is in the horizontal position shown in Fig. 1, it receives the sheaves from the binding-platform (not shown) of the harvester. When a sufficient number of sheaves 65 to make a shock have accumulated on the carrier, the operator, by means of the lever F, inclines the carrier to the position shown in Fig. 2. As the upper ends of the legs b' are pivoted to the upper ends of the arms C, the inner open side of the carrier is caused to swing away from the harvester-sill A when the carrier is tilted, and thereby an opening is left between the opposing sides of the harvester-frame and the carrier, through which the 70 sheaves fall to the ground.

We claim—

The combination of the harvester-frame, having the upwardly and outwardly extending arms C at one side, with the sheaf-carrier 80 having the irregular U-shaped arms b attached to its ends near its inner side, the said arms having the upwardly and inwardly extending legs b', pivoted at their upper ends to the arms C, and the legs c, diverging from the legs b' 85 and having their outer ends, d, bent at right angles to form stops to bear against the arms C when the carrier is in a horizontal position, the vertical arm E on the outer side of the carrier, the lever F on the harvester-frame, 90 and the rod f, connecting the arm E and the lever F, substantially as described.

In testimony that we claim the foregoing as our own we have hereto affixed our signatures in presence of two witnesses.

CHARLES H. ELLIOTT.
GEORGE W. ELLIOTT.
